UNITED STATES PATENT OFFICE.

MICHAEL C. REGAN, OF THE UNITED STATES ARMY, ASSIGNOR OF SEVEN-TENTHS TO WILLIAM H. GANNETT, OF AUGUSTA, MAINE, AND WILLARD H. GILMAN, OF BOSTON, MASSACHUSETTS.

PROJECTILE.

SPECIFICATION forming part of Letters Patent No. 728,012, dated May 12, 1903.

Application filed July 21, 1902. Serial No. 116,371. (No model.)

To all whom it may concern:

Be it known that I, MICHAEL C. REGAN, of the United States Army, stationed at Fort Revere, in the town of Hull, in the county of 5 Plymouth and State of Massachusetts, have invented certain new and useful Improvements in Projectiles, of which the following is a specification.

This invention has for its object to provide 10 an explosive projectile comprising a plurality of separable sections adapted to be separated during the flight of the projectile and to fall at different distances from the point of discharge.

15 The invention consists in the improvements hereinafter described and claimed.

Of the accompanying drawings, forming a part of this specification, Figure 1 represents a longitudinal central section of a projectile 20 embodying my invention. Fig. 2 represents a side elevation of the projectile. Fig. 3 represents an end view showing the outer or primary section of the projectile, the inner sections being removed. Figs. 4, 5, 6, 7, 8, and 25 9 represent perspective views of the parts of the projectile.

The same reference characters indicate the same parts in all the figures.

In the drawings, *a* represents the outer or 30 primary section of my improved projectile, the same being made in the form of a cylindrical shell which is open at one end and has a head *a'* at the opposite end and a partition *a*² between the head *a'* and the open end of 35 the shell. Said partition has a screw-threaded opening, into which is screwed a plug *a*³, which forms a part of the wall of a powder-chamber *a*⁴. Said chamber is adapted to contain a charge of powder or other explosive 40 sufficient to explode the section *a*. *b* represents another section of the projectile, which I term the "secondary" section. The shown form of this section is similar to that of the primary section—that is to say, its outer end 45 is open, while its inner end is formed by a head *b'*, a partition *b*² being provided which is closed by a screw-plug *b*³, said plug forming part of the wall of a powder-chamber *b*⁴, adapted to contain a charge of powder sufficient 50 to explode the section *b*.

c represents an additional section which is formed to be inserted in the open end of the section *b* and has a closed outer end, which is preferably conical, the section *c* having a powder-chamber *c*⁴, adapted to contain a 55 charge of powder sufficient to explode the section *c*.

d represents an intermediate chamber interposed between the plug *a*³ of the primary section and the head *b'* of the secondary section. *d'* represents another intermediate chamber interposed between the plug *b*³ of the secondary section *b* and the inner end of the outer section *c*. The intermediate chamber *d* is adapted to contain a charge of powder sufficient to cause by its explosion the separation of the section *b* from the section *a* and to give the section *a* a backward impulse while giving the section *b* a forward impulse. The intermediate chamber *d'* is adapted to contain a charge of powder sufficient by its explosion to separate the section *c* from the section *b*, giving the section *b* a backward impulse and the section *c* a forward impulse.

75 Means are provided for successively igniting the charges of powder in the several chambers after the projectile has been discharged from the gun, the charges being exploded in the following order: first, the charge 80 in the intermediate chamber *d*; second, the charge in the chamber *a*⁴ of the primary projectile; third, the charge in the intermediate chamber *d'*; fourth, the charge in the chamber *b*⁴ of the secondary projectile, and, fifth, 85 the charge in the chamber *c*⁴ of the projectile *c*. The explosion of the charge in the first intermediate chamber *d* causes the separation of the secondary projectile *b* from the primary projectile, the former carrying with 90 it the outer projectile *c*. A backward impulse is given to the primary projectile and an additional forward impulse to the secondary projectile. The charge of powder in the chamber *a*⁴ of the primary projectile is ignited at a later period by the ignition of the charge in the intermediate chamber *d*, so that the primary section is exploded after its separation from the secondary projectile. After 95 the secondary projectile *b* has advanced a 100

predetermined distance the charge in the intermediate chamber d' is ignited, causing the separation of the projectile c from the projectile b , the former being given a forward 5 and the latter a backward impulse, after which the charge in the chamber b^4 of the secondary section is ignited, causing the explosion of said projectile. The outer projectile c continues its forward flight, and after a predetermined length of time it is exploded by 10 the ignition of the charge in the chamber c^4 .

The means by which the charges are exploded successively, as above stated, are as follows:

15 f represents the time-fuse, which is contained in a brass tube f' , inserted in an orifice formed in the head of the primary section a and in a sleeve a^3 , formed on said head and extending through the chamber a^4 and into the plug a^3 .

20 $g g$ represent time-fuses extending from the intermediate chamber d into the chamber a^4 of the primary section, said fuses being contained in brass tubes $g' g'$, inserted in orifices 25 formed for their reception in the plug a^3 .

25 h represents a time-fuse extending through a tube h' and a sleeve h^5 from the intermediate chamber d to the intermediate chamber d' .

30 $i i$ represent time-fuses extending from the intermediate chamber d' to the chamber b^4 of the secondary section, said fuses i being contained in tubes i' , inserted in the plug b^3 .

35 j represents a time-fuse extending from the intermediate chamber d' through a tube j' , inserted in the inner end of the outer section c , the fuse j entering the powder-chamber of said outer section.

40 It will be seen that when the projectile as a whole is discharged from a gun the time-fuse f is ignited and that after the projectile has traveled a given distance the fuse f will ignite the charge in the intermediate chamber d . The ignition of this charge besides separating the sections a and b ignites the 45 fuses $g g$, causing the explosion of the charge in the chamber a^4 . After the separation of the sections a and b the latter, carrying the outer section c , continues its forward movement until the burning of the fuse h ignites

50 the charge in the intermediate chamber d' , whereupon the sections b and c are separated, as above stated, the fuses $i i$ being at the same time ignited. Section b therefore falls and is exploded during its descent, the section c continuing in its forward movement 55 until exploded by the ignition of its charge by means of the fuse j .

60 The intermediate chambers d and d' are formed by coinciding cavities provided in the plugs a^3 and b^3 and the inner ends or heads of the sections b and c , said chambers being preferably of the form shown in Fig. 1. The charges of powder in the intermediate chambers are preferably contained in sheet-metal 65 capsules k , formed to fit the walls of said chambers. The tubes containing the time-fuses are formed to project into the interme-

70 diate chambers, their projecting ends being preferably of a tapering or conical form. The capsules are provided with orifices formed and arranged to receive the projecting portions of the tubes. The said orifices are preferably formed by cutting slits in the walls of the capsules, the slits forming V-shaped 75 tongues which are normally in position to prevent the escape of powder from the capsule, the tongues being adapted to be bent inwardly by the projecting conical portions of the fuse-tubes when the parts are assembled, so that the ends of the fuse-tubes project into 80 the capsule, as shown in Fig. 1.

The internal surface of the section a , the external and internal surfaces of section b , and the external surface of the section c are 85 preferably rifled, as indicated in Figs. 4, 5, 85 and 6, the twist of the rifling-grooves being relatively slight, the twist including only about one-fourth of an inch on the periphery of each rifled surface.

90 m represents a copper band which encircles the section a near its inner end.

95 Among the advantages of this improved shell may be mentioned the following: First, it is particularly adapted for use as a range-finding shell owing to the fact that its sections drop at different points during the flight of the shell, the distance at which each section is exploded being determined by the length of the fuses; secondly, the separation 100 of the shell into sections which are exploded at different points, greatly increasing the effectiveness of the shell, it being well known that the explosion of several small shells at different points is liable to be more destructive than the explosion of a single larger shell; 105 thirdly, the sectional construction and the provisions for separating the sections at different points in the flight of the shell and for giving each an additional forward impulse 110 enable the outer section to be thrown to a great distance with a relatively small expenditure of powder.

115 There are many other features of advantage; but the above-stated are deemed to be sufficient for the present purposes.

I claim—

1. A projectile comprising a plurality of nested sections each having a powder-chamber, one or more intermediate powder-chambers interposed between the sections, and means for successively igniting the charges in all of said powder-chambers in the order specified.

2. A projectile comprising a primary section formed as a shell open at its outer end, 125 and having a powder-chamber at its inner end, a secondary section removably inserted in the primary section, an intermediate powder-chamber interposed between the two sections, and means for successively igniting the 130 charges in the said chambers in the order specified.

3. A projectile comprising a primary section formed as a shell open at its outer end,

- and having a powder-chamber at its inner end, a secondary section removably inserted in the primary section, an intermediate powder-chamber interposed between the two sections, a time-fuse extending from the exterior of the primary section to the intermediate chamber, and a time-fuse extending from the intermediate chamber to the chamber of the primary section.
- 5 4. A projectile comprising a primary section formed as a shell open at its outer end, and having a powder-chamber at its inner end, a secondary section removably inserted in the primary section, and having a powder-chamber, an intermediate powder-chamber interposed between the two sections, a time-fuse extending from the exterior of the primary section to the intermediate chamber, a time-fuse extending from the intermediate 10 chamber to the chamber of the primary section, and a time-fuse extending from the intermediate chamber to the chamber of the secondary section.
- 15 5. A projectile comprising a plurality of nested sections the inner section having a powder-chamber, an intermediate powder-chamber, interposed between the sections, a powder-holding capsule in said intermediate chamber, a fuse-holding tube affixed to the

inner section, said tube projecting into the 30 intermediate chamber and entering a perforation formed in the capsule, and a time-fuse extending through said tube.

6. A projectile comprising first a primary section open at its outer end and having a 35 powder-chamber at its inner end, and a screw-threaded plug forming a part of the wall of said chamber, said plug having a cavity in its outer face and fuse-holding tubes projecting into said cavity, the primary section having also a sleeve extending through the powder-chamber to said plug, and a fuse-holding tube located within said sleeve and projecting into said cavity, secondly, a secondary section removably inserted in the primary section and having a cavity in its inner end coinciding with the cavity in said plug, and a fuse-holding tube projecting into said cavity, and thirdly, a capsule inserted in said coinciding cavities and having openings arranged to receive the projecting ends of said fuse-holding tubes.

In testimony whereof I have affixed my signature in presence of two witnesses.

MICHAEL C. REGAN.
